UNITED STATES PATENT OFFICE.

DAVID N. CARVALHO, OF NEW YORK, N. Y., ASSIGNOR TO THE CELLULOID MANUFACTURING COMPANY, OF SAME PLACE.

PHOTOGRAPHIC BACKGROUND.

SPECIFICATION forming part of Letters Patent No. 237,247, dated February 1, 1881.

Application filed November 22, 1880. (No specimens.)

To all whom it may concern:

Be it known that I, DAVID N. CARVALHO, of New York, in the county of New York and State of New York, have invented a new and 5 useful Improvement in Photographic Backgrounds, of which the following is a specification.

The invention relates to an improvement in the manufacture of backgrounds used in the 10 photographic art.

It has been customary heretofore to employ a background in the form of a screen or frame, which has usually consisted of a painting or picture on canvas which has been placed in 15 position in the rear of the subject. The use of a background of this character has involved a great many difficulties and annoyances, and by reason of the expense and other circumstances it has been impossible to use more than 20 a limited number of effects in a gallery. Another method has been to produce a background on glass and gelatine, to all intents and purposes an ordinary negative, which has been used in connection with the negative em- 25 ployed in taking the subject, the two being secured together in a printing or pressure frame in the usual way, or by double-vignetting. There are many objections, however, to this class of backgrounds, owing to the diffi- 30 culty in using them in the pressure-frame, the great danger of injury by abrasion or break- age, the fading or loss of tint of the negative, and other circumstances.

To obviate those and other objections is the 35 object of my invention, which is effected by the employment of a background formed of translucent celluloid or other analogous plastic material.

The invention consists, essentially, in print- 40 ing or otherwise applying a design illustrating a scene upon a thin piece of translucent or transparent celluloid or other analogous plastic material, which is used substantially in the manner that backgrounds on glass and 45 gelatine have heretofore been used.

By preference the design or picture will be printed by any mechanical means upon the

sheet of celluloid, the size and shape being adapted to the size and shape of the photographic print in connection with which it is 50 intended to be used. By this means a great variety of backgrounds may be produced in connection with each subject, it being only necessary to change the background when a fresh piece of paper is introduced into the 55 printing-frame, with the sheet of celluloid lying between the negative and sensitive paper.

One of the advantages of my invention, to which I direct particular attention as being of especial moment, is that by the use of a thin 60 sheet of celluloid the operator is enabled to bring the background into much more intimate relations with the negative, so that the contact between the negative and background is much more perfect, and, as a consequence, 65 the picture made much sharper and clearer. I therefore preferably, in using my improved background in the printing-frames, employ as great pressure as can carefully be applied in locking the frame.

The background made of celluloid is inex- 70 pensive and not liable to injury by any ordinary use. It may be quickly and easily applied, and is capable of receiving and perma- nently retaining the most elaborate design.

I do not limit myself to the application of the design or scenic effect in any particular way; but

What I claim as new, and desire to secure by Letters Patent, is—

As a new article of manufacture, a photo- 80 graphic background consisting of a sheet of translucent or transparent celluloid or other analogous material bearing a scenic design, substantially as described.

In testimony that I claim the foregoing im- 85 provement in backgrounds of celluloid or anal- ogous plastic material, as above described, I have hereunto set my hand this 12th day of November, 1880.

DAVID N. CARVALHO.
